UNITED STATES PATENT OFFICE.

GEORGE W. SMILLIE, OF NEWARK, NEW JERSEY.

CAR-COUPING.

SPECIFICATION forming part of Letters Patent No. 402,775, dated May 7, 1889.

Application filed February 1, 1888. Serial No. 262,674. (No model.)

To all whom it may concern:

Be it known that I, GEORGE W. SMILLIE, a citizen of the United States, residing at Newark, in the county of Essex and State of New Jersey, have invented certain new and useful Improvements in Car-Couplers, of which the following, taken in connection with the drawings furnished, is a specification.

My invention relates to that class of car-couplers in which the connecting-link is automatically supported in a horizontal position, when desirable, by one of the coupling-sockets, yet allowed to yield in the proper direction when engaging with another coupler when upon the same or a different plane, it being an improvement upon inventions for which patents were granted to me July 8, 1884, and April 19, 1887; and it consists, principally, in the means, factors, and combinations of such by which the coupling is made more effectual, useful, and convenient for the various purposes intended, the object of which is to so form the coupling-heads that they may serve the double purpose of "buffers" and "coupling-sockets" and by their peculiar construction save the link connective at its pivotal points from injury when in practice.

Another object is to so construct the coupling-head that it may hold the coupling-pin loosely suspended upon a notch or rest when not connected with the other, that the jolt or jar caused by the contact of a car backed up for connection will loosen the said pin from its position and drop through the link into position without the aid of a person to assist in their union.

Another object is to hold the link-pin securely suspended above the link when the car is intended to stand without connection with others, as when to be left upon switches or side tracks, all of which will be hereinafter fully described, and pointed out in the claims.

Referring to the drawings, Figure 1 represents a front elevation of my improved coupler and buffer with levers, catches, and stops for suspending and operating the coupling-pin, which parts are attached to the front of a car-frame. Fig. 2 represents a sectional view of my improved coupling and buffer-head, showing the coupling-pin supported above the link. Figs. 3 and 4 repre-

sent a front and edge view of a stop serving to check the upward movement of the coupling-pin, lever, and supporting-catch; Fig. 5, 55 edge view of left lever and supporting-catch, the front of which is shown in Fig. 1. Fig. 6 represents a catch adapted for supporting or holding the lift-lever with coupling-pin "up" when desired, being a modification of 60 that shown in Fig. 5.

Referring to the drawings, A represents the draw-head, substantially of the same form as that shown in the first of the patents hereinbefore referred to, with the exception of the 65 outer extremity or head, which, instead of being "hopper-shaped" or flaring out uniformly, or nearly so, from the center, as that shown in my patent of July 8, 1884, I reinforce by thickening the upper portion of the 70 same and drop or lower the upper surface or edge slightly in order to bring it nearer on the same line or level with the main portion of the said draw-head, in order to gain the additional strength resulting thereby, and extend 75 or project it beyond the lower edge or front surface and sides of the said coupling-head to form a bearing-surface with a broadened face, as more clearly appears in Figs. 1 and 2 of the drawings. This feature has been found 80 in practice to be very important, as it not only protects the lower face surface of the coupling-head from injury and bruises by frequent concussion of engaging parts in practice, thereby preventing the hinged connective which holds 85 the link from being battered, but it also enables the constructor to dispense with the buffers usually employed, generally located upon each side of the draw-bar or coupler upon the car-frame, thereby allowing the train-men additional space between the ends of the cars, and consequently additional security to themselves when for any reason they are called upon to act between the ends of connecting cars, and thus the danger of coupling and 90 uncoupling of cars is materially diminished.

B represents a vertical opening or receptacle in the said draw-head for the admission of the coupling-pin C; D, a spring-actuated plunger operating within a longitudinal chamber, e, in the said draw-head. The said plunger is thrown across the opening B when the coupling-pin is drawn above the said opening by the spring d.

The coupling-link E is loosely secured to the draw-head through the medium of a connective (shown at F) pivotally united at both ends, and when in position for coupling is held horizontally, or nearly so, to engage readily with the co-operating draw-head, the link being wider than the plunger and the chamber with its recesses within which the said link is sustained in position. (More fully described in my patent of July 8, 1884.)

b represents a step or recess forming a rest located in one side of the said opening or receptacle B to form a support for the coupling-pin C when drawn above or withdrawn from the coupling-link. In order that the coupling-pin may catch and keep its position on the said rest b, I form one side of the said pin straight, or nearly so, to its end and round or tapering on the side opposite the former, as shown at c in Fig. 2.

The use of the pin and rest b, as described, is required principally in those cases where the coupler is not provided with a lever or other similar means for withdrawing and supporting the coupling-pin. When a car is to be uncoupled, the pin C is raised or drawn from its position within the coupling-link and supported on the rest b, thus allowing the cars to uncouple without further assistance on the part of the operator, and when the cars come together the plunger D is by the jolt thrown back within the chamber e on engagement with the coupling-link, said link being held by the coupling-head horizontally, or nearly so, as before described, and the jar caused by the colliding or coming together of the cars is usually sufficient to jar or throw the coupling-pin from its support on the rest b into position within the coupling-link, and by so doing a single person can couple the same number of cars formerly requiring several men to do.

F' represents a lever adapted to be fulcrumed to the face or frame of a car, provided with a fixed arm, G, extending therefrom and connected to the coupling-pin C through the medium of a link, H. The said lever F' is provided with the arms f'f, extending at right angles therefrom, all arranged and operated substantially as described and shown in my patent of April 19, 1887.

i i represent suitable fulcrum-bearings for the said lever F', secured to the face or frame of a car and on each side of the arm G. I represents a stop of suitable material adapted to be secured at its lower end to the face or frame of a car, and is provided with an angle or bend, (more clearly shown in Figs. 3 and 4,) in order to throw the upper part of the said bar from the face of the car in order to allow it to extend beyond the face of the lever F'.

J represents a slot or guideway in the upper part of the said stop, through which the fixed arm or extension G projects. The length of the said slot J is adapted to be varied by an adjustable screw, J', located at and

projecting through the upper end of the stop, against which the arm G may strike or rest when the coupling-pin is drawn up to prevent the said pin from being withdrawn or jerked from its proper position within the opening or receptacle B in addition to the pintle or projection k, with which the said coupling-pin is provided at or near its end. It is obvious, however, that other suitable devices may be secured in proximity to arms G, or near the handles f and fulcrum-bearings i, as shown in Figs. 1 and 5 of the drawings, and forming a stop for the arm G; or, again, the arm G may be provided with an arm or extension of suitable length on the side nearest the car.

The arm G, when drawn or raised up within the slot J for the purpose of drawing up the coupling-pin, is adapted to be held in its raised position by a stop consisting of a catch (shown at L) pivotally secured to the said stop I at one side of the slot J, as shown in Fig. 3. This catch may be operated in one direction by a spring in a manner to throw the same across the slot or opening J to engage or catch the arm G and hold the same in suspension. When it is desired to have the coupling-pin drop in position, disengagement of the catch is accomplished by a line or rod attached to the said catch L, the free end of which may be secured to the top, side, or any other desired position on the car or frame thereof.

Figs. 5 and 6 represent different means for operating the coupling-pin.

The chief object of my several catches and supports is to support the coupling-pin in a raised position when not desired to have the same operate automatically, as hereinbefore described.

In Fig. 5, p represents a movable support for the arm or extension f to rest on and adapted to be supported on the catch p'.

In Fig. 6 the support p is secured at the side of the car or frame and provided at its end with a notch or opening to engage one of the several notches located on the under side of the arm f.

Having thus set forth my invention, what I claim as new, and desire to secure by Letters Patent of the United States, is—

1. The combination, in a car-coupling provided with a draw-head, link, coupling-pin, and a horizontally-arranged lever to which said coupling-pin is connected, provided with arms at each end thereof, of one or more bars or rods pivotally secured to the frame of the car, adapted to be supported by a catch when in a raised position to support said arms, substantially as described.

2. The combination, in a car-coupling provided with a draw-head having a thickened upper face, link, coupling-pin, and a projecting horizontally-arranged lever provided with a fixed arm or projection extending therefrom for connection with said coupling-pin, of an upright arm adapted to be secured to the face of the car, provided with a longitudinal open-

ing through which the fixed arm of said horizontal lever projects, and an adjusting-screw arranged in said upright arm, substantially as described, and for the purpose set forth.

5 3. In a car-coupling, the combination, with a draw-head provided with a vertical opening or pin-receptacle having a rest or support in one side thereof, a link, coupling-pin, and a horizontally-arranged lever having a fixed arm

extending therefrom, of a vertically-arranged arm provided with an opening in which said fixed arm operates, an adjusting-screw, and a spring-catch, substantially as described, and for the purpose set forth.

GEO. W. SMILLIE.
